United States Patent Office

Des. 226,795
Patented May 1, 1973

226,795

PORTABLE CUSHION

Andrew Johnson, 3140 N. 12th St.,
Philadelphia, Pa. 19133

Filed Aug. 5, 1970, Ser. No. 24,310

Term of patent 14 years

Int. Cl. D6—09

U.S. Cl. D6—201

Fig. 1

Fig. 2

FIG. 1 is a side elevational view of a portable cushion showing my new design;

FIG. 2 is a bottom plan view thereof;

FIG. 3 is a side perspective view;

FIG. 4 is a top plan view; and

FIG. 5 is an end elevational view.

I claim:

The ornamental design for a portable cushion, as shown.
